(57) CLAIM

The ornamental design for an animated image for a portion of a display screen, as shown and described.

DESCRIPTION

FIG. 1 is a front view of a first image in a sequence for a transitional image for a portion of a display screen, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the animated image sequentially transitions between the images shown in FIGS. 1-7.

The broken line of the portion of the display screen in all views is for illustrative purposes only and forms no part of the claimed design.
